DESIGN FOR A STORAGE TANK

George T. Horton, Chicago, Ill., assignor to Chicago Bridge & Iron Company, Chicago, Ill., a corporation of Illinois

Application July 31, 1936, Serial No. 64,162

Term of patent 14 years

To all whom it may concern:

Be it known that I, George T. Horton, a citizen of the United States, residing at Chicago, in the county of Cook and State of Illinois, have invented a new, original, and ornamental Design for a Storage Tank, of which the following is a specification, reference being had to the accompanying drawing, forming a part thereof, in which:

Figure 1 of the drawing is a top plan view of a storage tank; and Fig. 2 is a view in side elevation thereof, showing my new design.

I claim:

The ornamental design for a storage tank as shown.

GEORGE T. HORTON.
